United States Patent Office

Des. 183,307
Patented Aug. 5, 1958

183,307

REFRIGERATOR CABINET

Edwin O. Grahn, Birmingham, Mich., assignor to General Motors Corporation, Detroit, Mich., a corporation of Delaware

Application October 30, 1956, Serial No. 43,587

Term of patent 14 years

(Cl. D67—3)

Fig. 1

Fig. 3

Fig. 2

Figure 1 is a front perspective view of a refrigerator cabinet, showing my new design;

Figure 2 is a top plan view thereof; and

Figure 3 is a side elevational view thereof.

The essential features of my design reside in the portions shown by full lines in the drawing.

I claim:

The ornamental design for a refrigerator cabinet, as shown and described.
